[57] CLAIM

The ornamental design for a fluorescent lamp, substantially as shown and described.

DESCRIPTION

FIG. 1 is a front elevational view of a fluorescent lamp showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is an enlarged cross-sectional view taken along line 6—6 of FIG. 4;

FIG. 7 is a front elevational view of a second embodiment;

FIG. 8 is a left side elevational view thereof;

FIG. 9 is a right side elevational view thereof;

FIG. 10 is a top plan view thereof;

FIG. 11 is a bottom plan view thereof;

FIG. 12 is an enlarged cross-sectional view taken along 12—12 of FIG. 10;

FIG. 13 is a front elevational view of a third embodiment;

FIG. 14 is a left side elevational view thereof;

FIG. 15 is a right side elevational view thereof;

FIG. 16 is a top plan view thereof;

FIG. 17 is a bottom plan view thereof; and

FIG. 18 is an enlarged cross-sectional view taken along line 18—18 of FIG. 16.
